United States Patent Office.

JOHN S. CAMPBELL, OF NEWTON, NEW JERSEY.

Letters Patent No. 78,777, dated January 28, 1868.

IMPROVEMENT IN CHECK-REIN HOOKS.

The Schedule referred to in these Letters Patent and making part of the same.

TO ALL WHOM IT MAY CONCERN:

Be it known that I, JOHN S. CAMPBELL, of Newton, in the county of Sussex, and State of New Jersey, have invented a new and useful Improvement in Check-Rein Hooks or Terrets for Harness; and I do hereby declare that the following is a full, clear, and exact description of the same, reference being had to the accompanying drawings, making a portion of this specification, in which—

Figure 1 is a vertical longitudinal section, representing the hook or terret in an open condition, to permit the check-rein to be hooked over the same.

Figure 2 is a side view of the same as closed, to prevent the detachment of the check-rein.

Similar letters of reference indicate corresponding parts in both figures.

The object of this invention is to prevent the check-rein of a harness from becoming casually detached from the hook or terret over which the same is hooked when in use, and to this end the invention consists in a swinging bar, combined with a plate punctured in the centre for attachment to the aforesaid hook or terret, so that it may be turned forward and downward, to open the hook, and allow the check-rein to be placed thereon, and turned backward and upward in such manner as to close the opening of the hook, and thus prevent the aforesaid rein from slipping off.

To enable others to understand the nature and construction of my invention, I will proceed to describe it with reference to the drawings.

A represents the check-rein hook or terret, which may be of any appropriate form, and attached to the saddle-tree of the harness by the broad-headed bolt a . Placed underneath the head a' of this bolt is a thin flat metal plate, b , the rearwardly-projecting portion of which is divided by two longitudinal slots, so that a short tongue, c' , is formed, which serves as a spring, the purpose of which will be presently set forth. Those portions of the said rear part of the plate b at each side of this spring c' have hinged or pivoted to them a bar, B , in such manner that the said bar may be either turned forward and downward over the head of the bolt a , to open the hook, as shown in fig. 1, or be turned upward into a nearly or quite vertical position, to close the opening, at a'' , of the said hook, as shown in fig. 2, the pivoted end of the bar B being made with two flat surfaces, so arranged in relation with the spring c' that the said spring c' , acting upon one surface or the other, will retain the bar in either its upright or depressed position, as the case may be.

When the bar is depressed, as just set forth, the check-rein may be slipped over the hook in the usual manner, and as indicated in red outline in fig. 2, which being done, the aforesaid bar is turned up to close the opening of the hook, as shown in the said figure, thereby preventing all liability of the casual slipping or disengagement of the check-rein from the hook.

What I claim as my invention, and desire to secure by Letters Patent, is—

The hinged tongue B , in combination with the plate b , for attachment to the check-rein hook, substantially as set forth.

JOHN S. CAMPBELL.
